UNITED STATES PATENT OFFICE.

SAMUEL COHN, OF NEW YORK, N. Y., ASSIGNOR TO MANTLE MACHINERY & PATENTS COMPANY, OF NEW YORK, N. Y., A CORPORATION OF NEW YORK.

MANTLE-DARNING MACHINE.

1,161,847.

Specification of Letters Patent. Patented Nov. 30, 1915.

Original application filed April 17, 1912, Serial No. 691,425. Divided and this application filed January 20, 1914. Serial No. 813,298.

To all whom it may concern:

Be it known that I, SAMUEL COHN, a citizen of the United States, residing at New York, in the county and State of New York, have invented a new and useful Improvement in Mantle-Darning Machines, of which the following is a full, clear, and exact description, reference being had to the accompanying drawings, forming part of this specification, in which—

Figure 1 is a transverse sectional view of a portion of a darning machine with one form of my improved mechanism attached. Fig. 2 is a similar view of a portion of the mechanism shown in Fig. 1, showing the parts in different position. Fig. 3 is a view similar to Fig. 2, showing the parts in still another position. Fig. 4 is a sectional plan view on the line IV—IV of Fig. 1. Fig. 5 is an inverted plan view of a mechanism shown in Fig. 1. Fig. 6 is a sectional view on the line VI—VI of Fig. 4, showing a mantle in position in the machine. Fig. 7 is a detail sectional view on the line VII—VII of Fig. 5, showing the pawl for rotating the mantle supporting member of the darning machine. Fig. 8 is a bottom plan view of a portion of the mantle showing a view of the stitches. Fig. 9 is an inverted plan view of a finished mantle. Fig. 10 is a view similar to Fig. 9 of a modified form of mantle.

My invention relates to a darning machine for darning mantles and forms a division of my application Serial No. 691,425, filed April 17, 1912.

The object of my invention is to provide a machine which will avoid the difficulties incident to the thick mass of longitudinally extending folds which are gathered toward the center of the closed end of the mantle.

In accordance with my invention the end of the mantle is gathered, but the folds are not pulled together and compacted in longitudinal form. On the contrary, a hole is left of considerable size at the center of the mantle, the gathered portions extending inwardly in a transverse direction toward this hole, and by means of an impregnated thread the hole is mechanically darned so as to close it with the same material as that of the mantle.

In carrying out the invention, a circular

row of stitches is preferably formed around the hole to fix the mantle forming threads in 55 position, while the hole is darned by means of a plurality of radial and tangentially disposed stitches extending across the opening.

The precise nature of my invention will be best understood by reference to the accompanying drawings in which I have shown one embodiment of my invention, it being premised, however, that various changes may be made in the details of construction and general arrangement of the 65 parts, as well as their timed operation, without departing from the spirit and scope of my invention, as defined in the appended claims.

The mantle is secured to the supporting 70 ring in the usual manner and the lower shirred portion is drawn together and tied by a drawstring to fix the size of the hole at the end. The blank is then placed in the machine and the hole is darned, as herein- 75 after described.

Referring to Figs. 1 to 9 of the drawings, the numeral 2 designates the bed plate of a sewing machine to which I have attached one form of my darning machine. 3 and 4 80 are rock shafts, journaled in projections extending downwardly from the bed plate 2, and which are arranged to be rocked by the sewing machine mechanism in timed relation to the reciprocation of the needle. 85 Connected to the shaft 4 are two levers 5 and 5^a, and pivotally connected to the upper lever 5^a is a feed arm 6, the other end of the arm being provided with a fork 7 which engages an eccentric on the shaft 3. 8 designates a shaft which is rotatably mounted in a bracket 9 connected to the feed arm 6; and connected to this shaft 8 is a ratchet wheel 10 and a cam wheel 11. The cam wheel 11 is provided with an equal number 90 of projections and recesses, the number of recesses and projections being equal to the number of teeth on the ratchet wheel 10. Pivotally connected to the lever 5 is a reciprocating pawl 12, which is provided with 95 a hook adapted to engage the teeth of the ratchet wheel 10 and move it the distance of one tooth when it is moved in one direction. 13 is a leaf spring connected to the bracket 9 and engaging the hooked end of 100 the pawl 12 for maintaining it in engage- 105

ment with the ratchet wheel 10. Connected to the top of the bed plate 2 is an auxiliary bed plate 14 which is provided with side guides 15 in which is seated a reciprocating plate 17. 18 is a lock bar seated in a transverse groove in the slide plate 17 and in recessed portions 19 in the upper faces of the side guides 15, which lock bar forms a stop for the reciprocating plate 17 when moved 5 in one direction. This reciprocating plate 17 is moved in one direction by means of the gyratory feed arm 6, as hereinafter described, and is moved in the other direction by a coiled spring 20 mounted on a screw or 10 pin 21 on one of the guide plates 15. Rotatably mounted in the reciprocating plate 17 is a flanged ring 22 which is provided with ratchet teeth 22^a on its lower face. Connected to the central portion of the gyratory feed arm 6 is a plate 23; and connected 15 to this plate 23 is a spring arm 24 above the cam plate 11. Extending downwardly from the spring arm 24 is a pin 25 which is adapted to rest on the cam plate 11, and extending 20 upwardly from the outer end of this spring arm is a tooth 26. 27 is a tooth which extends downwardly from the plate 17 and in line of movement of the tooth. These teeth are so arranged that the slide plate will be 25 moved to the left when the arm 6 is moved to the left, if the arm and tooth are in their raised positions to move the mantle in a longitudinal direction to form a stitch on the opposite side of the opening, as hereinafter 30 described. The flanged ring 22 is rotated by means of a pawl 28 connected to the plate 23 and is adapted to engage the teeth on the ring 22 to move the ring the distance of one tooth when the feed arm is raised and moved 35 to the right and when the tooth 26 is in its lowermost position. 32 is a retaining pawl connected to the slide plate 17 to retain the flanged ring 22 in its shifted position. 33 designates the head of a sewing machine in 40 which is mounted the usual reciprocating needle bar 34 carrying a needle 35. 36 is a spring surrounding the needle and is arranged to retain the fabric in position during the upward movement of the needle and 45 which takes the place of the usual presser foot for holding the fabric during the formation of the stitch, but is raised from the fabric after the needle has been elevated to a predetermined point to permit the fabric to be shifted to form the various stitches. Attached to the usual presser foot bar 37 is a 50 ring 38 which is arranged to engage the supporting lugs on the mantle ring, as shown in Fig. 6. Extending upwardly from the flanged ring 22 is a pin 39 which is adapted 55 to engage one of the supporting lugs on the mantle ring to positively rotate the mantle with the ring 22.

60 I have merely shown the needle of the sewing machine and have omitted the stitch

forming mechanism of the sewing machine below the body plate, as this mechanism does not form any part of my invention.

After the draw string has been drawn and tied, as heretofore described, the mantle is 70 placed in the ring 22, as shown in Fig. 6, and is held in position by means of the ring 38 on the presser foot bar 37. The sewing machine is then operated so that the needle descends and passes through the fabric at 75 the point *a* in Fig. 8 and forms a stitch, while the actuating mechanism below the bed plate is in the position shown in Fig. 3. As the needle is elevated, after forming the first stitch, the shaft 3 is rocked to lower the 80 arm 6, and the shaft 4 is also rocked to move the arm 6 to the right and before the needle descends to and passes through the fabric, the shafts are rocked to raise the arm 6 and move it to the left, as shown in Fig. 1. The 85 mechanism is so timed that the projection 25 on the bottom of the spring 24 is in engagement with a raised portion on the cam 11, which will retain the tooth 26 in this elevated position so that it will engage the 90 tooth 27 on the plate 17, and as the arm 6 is moved to the left it will move the slide plate 17, together with the ring 22 and the mantle, to the left. The needle now passes through the fabric to form a stitch at *b*, the thread 95 between the stitches extending as a chord across the opening in the end of the mantle. As the needle ascends after the formation of the stitch *b*, the arm 6 will be moved to the right during the reverse movement of the 100 rock shaft 4, and the slide plate 17 will be returned to its initial position by the spring 20. During this reverse movement of the rock shaft 4, the pawl 28 will be moved to the left and rotate the ratchet wheel 10 the 105 distance of one tooth which will move the cam so that the pin 25 will rest in one of the recesses, as indicated in Fig. 3. The arm 6 is again raised and moved to the left and as the tooth 26 is lowered it will not engage the tooth 27 to move the plate 17 to 110 the left, but the pawl 28 will engage one of the teeth 22^a and rotate the ring 22. The needle now descends and forms a stitch at *c* and the thread will extend diametrically 115 from the stitch *b* to the stitch *c* across the opening in the bottom of the mantle. As the shafts 3 and 4 are again oscillated to move the arm 6 to the left, the tooth 26 will not engage the tooth 27, as the pin 25 is within 120 one of the recesses and the tooth 26 is below the tooth 27. The next stitch will be formed at *d*, the thread extending as a chord in a manner similar to the thread extending from *a* to *b*.

125 The above operations are repeated to form a plurality of radial and tangential stitches to darn the hole. If desired a plurality of stitches may be formed around the opening, either before or after the darning thereof. 130

The longitudinal movement of the arm 6 is considerably greater than the distance between teeth on the ring 22, and as the ring is only moved the distance of one tooth during the reciprocation of the arm 6, the shafts 3 and 4 are so timed that the pawl 28 will be held in engagement with the teeth 22^a long enough to move the ring 22 the distance of one tooth. The radially disposed threads 10 are laid during the reciprocation of the plate 17 during which time the ring 22 is not rotated as all of the parts move together, and the remaining threads which are in the nature of chords, each extending at one side of 15 the center of the opening are laid during the rotation of the ring 21. If desired, I may close the hole by placing a patch over it, then stitch the patch in place, as shown in Fig. 10. This is done by rotating the ring 20 instead of reciprocating it. In that case the pawl 12 would be disengaged from the ratchet wheel 10 when the cam 11 is in the position shown in Fig. 3, so that the plate 17 would not be reciprocated, but the ring 22 25 would be rotated during each reciprocation of the plate 17.

The advantages of my invention result from the provision of mechanism for rotating and reciprocating the mantle below the 30 needle of the sewing machine to lay radial and tangential threads between the various stitches formed by the machine.

I claim:

1. In apparatus of the character set forth, 35 the combination with a carriage having a back and forth movement and a work holder rotatably mounted thereon, of means for rotating the work holder, means for effecting a back and forth movement of the carriage, 40 common operating mechanism for both of said means, and means for intermittently causing the means that moves the work holder, to be moved to an inactive position.

2. In apparatus of the character set forth, 45 the combination with a carriage having a back and forth movement and a work holder rotatably mounted thereon, of a spring for moving the carriage in one direction, a pawl for moving the carriage against the action 50 of the spring, and mechanism for actuating the pawl to move the carriage and release it, and permit the spring to act and for rotating the work holder.

3. In apparatus of the character set forth, 55 the combination with a carriage having a back and forth movement and a work holder rotatably mounted thereon, of a spring for moving the carriage in one direction, a pawl for moving the carriage against the action 60 of the spring, a pawl for rotating the work holder, and mechanism for actuating the pawls, said mechanism including a device for moving the pawl into position to actuate the carriage and release it therefrom to permit the spring to move said carriage.

4. A mantle darning machine, comprising a reciprocating plate, a rotary mantle holder mounted on said plate, reciprocating mechanism below said plate, actuating connections for reciprocating said mechanism, a plurality of pawls connected to said mechanism, and actuating connections for controlling said pawls so that they will act alternately to reciprocate the plate and rotate the mantle holding device; substantially as 75 described.

5. In a machine for darning mantles, a machine bed, a carriage plate thereon, a work holder rotatably mounted on the carriage plate, a rock shaft beneath the bed, 80 and pawls operated by the rock shaft, one engaging the carriage plate to effect its movement, the other engaging the work holder to rotate it.

6. In a machine for darning mantles, a machine bed, a carriage plate thereon, a work holder rotatably mounted on the carriage plate, a rock shaft beneath the bed, 85 pawls operated by the rock shaft, one engaging the carriage plate to effect its back and forth movement, the other engaging the work holder to rotate it, a cam for moving one of the pawls into operative position, and means for periodically rotating the cam.

7. In mechanism of the character set forth, the combination with a rotatable work holder capable of back and forth movement and stitch forming mechanism co-operating therewith, of means including pawls for respectively rotating the work holder and giving it a back and forth movement, and means for alternately throwing one of said pawls into and out of operation.

8. In mechanism of the character set forth, the combination with a reciprocatory work holder and stitch forming mechanism co-operating therewith, of a feed arm, a pawl carried by the feed arm and movable into and out of coaction with the work holder, means for moving the arm back and forth, a rotary cam that engages the pawl to intermittently move it into said coaction, and a device operating with the feed arm for intermittently rotating the cam.

9. In mechanism of the character set forth, the combination with a reciprocatory slide and a work holding disk rotatably mounted therein, of two pawls respectively engaging the disk and slide for intermittently rotating and reciprocating the same, 120 means for moving the pawls back and forth, and means for intermittently moving the pawl that engages the slide into coaction therewith and permitting its disengagement therefrom.

10. In mechanism of the character set forth, the combination with a reciprocatory slide and a rotary work holding disk journaled therein, of stitch forming mechanism co-operating therewith, a rock shaft, a feed 130

arm connected thereto, pawls carried by the feed arm and coöperating respectively with the disk and slide, to effect their intermittent movements, a rotary cam journaled on 5 the arm and engaging one of the pawls, and ratchet mechanism operated by the rock shaft for intermittently rotating the cam.

11. In mechanism of the character set forth, the combination with a table, a rotatable work holder thereon having ratchet teeth, and stitch forming mechanism co-operating with the work holder, of rock shafts journaled beneath the table, an arm having its ends eccentrically connected to 10 the rock shafts, and a pawl carried by the arm and engaging the teeth of the work holder to effect a step-by-step rotation thereof.

12. In mechanism of the character set forth, the combination with a table, a re- 20

ciprocatory slide thereon, a work holder rotatably mounted in the slide and having ratchet teeth, and stitch forming mechanism co-operating with the work holder, of rock shafts journaled beneath the table on opposite sides of the work holder, an arm having a crank connection at one end with one of the rock shafts and an eccentric bearing at its other end with the other rock shaft, and a pawl carried by the arm between its 25 ends and engaging the teeth of the work holder to effect a step-by-step rotation thereof.

In testimony whereof, I have hereunto set my hand.

SAMUEL COHN.
